UNITED STATES PATENT OFFICE.

EMIL SCHUELKE AND JULIUS ROSS, OF MERIDEN, CONNECTICUT, ASSIGNEES TO THE NAPIER CO., OF MERIDEN, CONNECTICUT, A CORPORATION.

POWDER HOLDER.

Application filed July 10, 1925. Serial No. 42,650.

To all whom it may concern:

Be it known that we, EMIL SCHUELKE and JULIUS ROSS, citizens of the United States, residing at Meriden, in the county of New Haven and State of Connecticut, have invented a new and useful Improvement in Powder Holders; and we do hereby declare the following, when taken in connection with the accompanying drawings and the characters of reference marked thereon, to be a full, clear, and exact description of the same, and which said drawings constitute part of this application and represent, in-

Fig. 1 a plan view of a vanity-box showing our improved powder-holder located therein.

Fig. 2 a sectional view on the line 2—2 of Fig. 1, enlarged.

Fig. 3 a plan view of the powder-holder, detached.

Fig. 4 an edge view of the same.

Fig. 5 a sectional view on the line 5—5 of Fig. 3, enlarged.

Fig. 6 a plan view of the shutter, detached.

This invention relates to improvement in powder-holders particularly adapted for vanity-boxes of the type of powder-holder which consists of a top with openings therein, through which powder is extruded. The object of this invention is to provide means for extruding the powder, and the invention consists in providing a shutter with blades adapted to force powder through the openings. A further object of the invention is to provide means for firmly locating a powder-container in a vanity-box, and the invention consists in mounting a shutter on the under-side of a perforated top-plate, forming this shutter with radial blades and providing the box with a spring-arm adapted to engage with the under-side wall of a vanity-box,—all as hereinafter described and particularly recited in the claim.

In carrying out our invention, we employ a container comprising a top-plate 10, preferably concaved, and a downwardly-extending flange 11. The plate is formed with a plurality of powder-openings 12 and with a concentric slot 13. Connected with the underface of the top-plate is a shutter 14 formed with radial slots 15, the edges of which are turned downward to form blades 16. The shutter is also formed with a finger 17 which projects upward through the slot

13 and by which the shutter may be rotated. Powder having been placed in the container, the container is closed by a back 18 preferably bowed, and attached to this back is a spring-locking bar 19, the ends of which project slightly beyond the edges of the back-plate and are adapted to enter and engage with bayonet grooves 20 formed in opposite sides of the flange 11. Attached to the outer edge of the container is a tangential, spring-locking arm 21, formed at its outer end with an inwardly-offset finger 22. In the normal position, this spring stands at a tangent to the container, but is pressed toward the container to adapt it to be inserted into a vanity-box 23, the finger 22 springing outward to engage with an annular shoulder 24, near the upper edge of the box.

By rotating the shutter by means of the finger-piece 17, powder in the container will be forced by the blades 16 upward through the openings 12 in suitable quantity, these openings 12, however, being closed when the shutter is in either of its extreme positions, but when moved in one direction will force a sufficient amount of powder upward through the openings, in position to be removed by the usual puff.

With this construction, the powder-container is firmly held in a vanity-box, but can be freely removed when desired, as the fingers 17 and 22 may be caught by the nails of the thumb and first finger, so as to move the end of the spring 21 toward the side of the container and clear the shoulder 24 in the box. When in place, the spring provides sufficient friction, so that the container is not moved by the turning of the shutter.

We claim:

A powder-holder, comprising a top-plate formed with openings and with a concentric slot and having a downwardly-extending flange provided with bayonet grooves, a shutter bearing against the under-face of the top-plate, formed with slots, the edges of which form downwardly-turned blades, and a back-plate fitting within said flange and provided with a transverse bar, the ends of which engage with said bayonet grooves.

In testimony whereof, we have signed this specification.

EMIL SCHUELKE.
JULIUS ROSS.
